J. T. ANTHONY,
WOOTEN TYPE LOCOMOTIVE BOILER,
APPLICATION FILED FEB. 8, 1916.

1,229,382.

Patented June 12, 1917.

UNITED STATES PATENT OFFICE.

JAMES T. ANTHONY, OF EAST ORANGE, NEW JERSEY, ASSIGNOR TO AMERICAN ARCH COMPANY, OF NEW YORK, N. Y., A CORPORATION OF DELAWARE.

WOOTEN-TYPE LOCOMOTIVE-BOILER.

1,229,382.

Specification of Letters Patent. Patented June 12, 1917.

Application filed February 8, 1916. Serial No. 76,946.

To all whom it may concern:

Be it known that I, JAMES T. ANTHONY, a citizen of the United States, and a resident of East Orange, county of Essex, and 5 State of New Jersey, have invented certain new and useful Improvements in and for Wooten-Type Locomotive-Boilers, of which the following is a specification.

My invention relates to improvements in 10 locomotive boilers of the Wooten type which have firebox extensions within the barrel of the boiler forward of the grate.

The firebox of a Wooten type boiler differs 15 from others chiefly in the matter of its height. The distance between the grate and the crown sheet is much less than in locomotive fireboxes of other types. The reason of this peculiarity is that Wooten fireboxes are designed for use with anthracite coal; a 20 fuel which yields a very short flame, as compared with others, and which therefore necessitates the arrangement of the chief heating surface (the crown sheet) close to the fuel bed. The height of the firebox extension, sometimes called the barrel combustion 25 chamber, is determined by the height of the crown sheet as in other fireboxes. Another characteristic of a Wooten firebox is that the grate is placed almost on a level with 30 the floor of the extension.

It is claimed for the Wooten type firebox that by reason of its low height there is a 35 substantially equal distribution of the hot gases in the flues of the boiler; and that this and the attendant easy maintenance of the flues and the flue sheet, are advantages secured without material loss of heating value in the walls of the firebox, inasmuch as the latter are close to the fuel bed. Against the 40 admitted advantages of such fireboxes, I find that the flow of hot gases from grate to flues is so rapid and direct that the rear part of a Wooten firebox is much less effective than supposed.

It has been suggested that a cure may be 45 effected by providing Wooten fireboxes with inclined refractory arches of the kind used in bituminous coal burning locomotives and which in such locomotives have served to 50 obviate disadvantages similar to those here mentioned as pertaining to Wooten fireboxes. But extensive experiments conducted in the past have made it appear that the 55 lack of height in the Wooten firebox, and its narrow throat sheet, prevent the practical

and efficient use of such arches. Wooten fireboxes of the extension type are therefore customarily used without arches or baffle walls of any kind.

The object of my invention is to provide 60 within a Wooten type firebox a dividing wall and arch which shall perform the same desirable functions as the arches which are used in bituminous coal-burning fireboxes.

The manner in which I attain this object, 65 and the nature and particulars of my invention, will be understood on reference to the drawings that form part of this specification, and in which:—Figure 1 is a longitudinal section of a Wooten type locomotive 70 boiler embodying my invention on the line Y—Y of Fig. 2;—and Fig. 2 is a transverse section thereof on the line X—X of Fig. 1.

The familiar parts of a Wooten type firebox are as follows:—The boiler-barrel, 2;—the firebox sheet, 3;—the mud ring, 4;—the side sheets, 5, 5;—the crown sheet, 6;—the rear sheet, 7;—side water legs, 8, 8;—the rear water leg, 9;—the fuel door, 10;—and the throat sheet, 11;—the shallow front water leg, 12;—the flue sheet, 13;—and, the flues, 14. The grate, 15, usually occupies the 75 whole space within the confines of the mud ring, extending from side to side of the firebox and from the rear sheet, 7, to the throat sheet, 11.

The firebox-extension or barrel combustion chamber, B, is all that part of the firebox between the flue sheet, 14, and the throat 90 sheet, 11. The floor, 16, and sides, 16', of the extension, B, join the extension, 6', of the crown sheet which forms the top of the extension. The throat sheet usually extends only to the floor of the extension. In 95 my novel firebox it has a different form, which will be explained.

It will be noted that a Wooten firebox is of much less height than width. Instead of attempting to employ a refractory arch 100 extending upwardly and rearwardly from the lower part of the throat sheet, 11, I first divide the firebox into fire and combustion chambers by means of a vertical water wall or cross-leg positioned in the firebox-extension, B. I then construct an overhanging arch, C, rearwardly of the wall by means of arch tubes extending therefrom and refractory bricks placed on said tubes.

I form the cross wall or cross-leg above 110

referred to as a vertical transverse water leg which constitutes a vertical extension of the front water leg, 12, of the boiler. On reference to Fig. 1 of the drawings it will be seen that said wall or leg, W, has its rear wall formed by a portion, 11', of the throat sheet which extends above the floor, 16, of the extension, B. Its front wall, 11'', is formed by a plate which rises from the floor, 16, and is spaced forward from the plate, 11'. The edges of the plates, 11' and 11'', are tightly seamed to the side sheets, 5, 5, and the sheets, 16, 16'. The top, W', of the leg may be integral with the plates, 11', 11'', but may be more conveniently formed by a separate piece seamed thereto and to the side sheets.

It should be especially noted that the top, W', of the water leg, W, is lowest at its middle and curves upwardly from that point to the side sheets. By constructing the wall in this manner the water and steam are allowed to escape freely from the leg, W, into the side water legs, 8, of the boiler, and steam pocketing is avoided.

25 Those who are skilled in the art will understand that the walls, 11', 11", are secured by means of staybolts which pass through them; in the same manner as the other walls of the firebox are stayed.

30 of the firebox are stayed. Obviously, both the lower part and ends of the hollow metal wall or cross leg, W, are in free communication with all of the water legs or spaces of the boiler. The bottom sheet, 16, joins the sheet, 11" and should not be attached to the sheet, 11.

35 be attached to the sheet, 11.
The wall, W, may rise to the center of the combustion chamber, B, or even higher, if desired. When used alone it performs the function of partly separating the combustion chamber from the fire chamber, A. This amount of separation is not sufficient to insure the best results. Such results can only be secured through the employment of a large mass of refractory brick in the form of an arch, C, which extends rearwardly and upwardly from the wall, W, and overhangs a portion of the grate, 15. Most conveniently this wall is composed of a large number of refractory bricks, all of a size to 40 be passed through the fuel door, 10.
45
50

50 be passed through.
For supporting the arch bricks I employ
a sufficient number of longitudinally in-
clined water circulating arch tubes, 17.
These are arranged at sufficient height to
55 afford proper fuel and fire clearance between
the grate and the arch, C. As shown, the

arch tubes are spaced apart. Their lower forward ends are fastened in the upper part of the throat sheet, 11', and communicate with the interior of the wall, W. The rear ends of the arch tubes are in like manner fastened in the rear sheet, 7, near the top thereof. This arrangement affords sufficient inclination to insure the rapid flow of water through the tubes, 17. Fig. 2. I prefer that all

As best shown in Fig. 2, I prefer that all of the arch tubes shall be so positioned that their corresponding clean-out openings and plugs, 18, may be located in the forward sheet or wall, 11", of the water leg, W. But other arrangements of the tubes may be resorted to. It will be found desirable

In many cases it will be found desirable to provide the combustion chamber, B, with a cinder hopper and closure of the kind set forth in my prior Patent No. 1,118,615. 75

I desire it to be understood that the water containing cross wall herein described may be used to advantage even when the water tubes and the arch bricks are lacking. It should also be understood that the herein described wall, either with or without the arch tubes, may be installed in several types of barrel combustion chamber fireboxes and is not limited to Wooten type fireboxes, although it appears that the invention attains its greatest utility in fireboxes of the Wooten type. 80 85

Having thus described my invention, I claim as new and desire to secure by Letters Patent:—

Patent:— A locomotive boiler containing a firebox having a barrel combustion chamber or extension forward of its throat sheet, in combination with the cross water leg positioned in the mouth of said extension, and in open communication with the bottom and side water spaces or legs of the firebox, and there remaining a gas passage above the top of said cross water leg, a plurality of water 1 circulating arch tubes extending upwardly and rearwardly from the approximate top of said cross water leg, and a refractory brick arch composed of bricks supported by said tubes, said arch extending rearwardly from 1 said cross water leg and from side to side of the firebox proper, substantially and as to the purpose specified.

the purpose specified.
In testimony whereof, I have hereunto set
my hand this 8th day of January, 1916.

JAMES T. ANTHONY.
